ESIGN.

C. E. HAVILAND.
DISH.

No. 21,381.

~~Patented~~ Mar. 8, 1892.

Fig. 2.

UNITED STATES PATENT OFFICE.

CHARLES ED. HAVILAND, OF LIMOGES, FRANCE.

DESIGN FOR A DISH.

SPECIFICATION forming part of Design No. 21,381, dated March 8, 1892.

Application filed July 23, 1889. Serial No. 318,430. Term of patent 14 years.

To all whom it may concern:

Be it known that I, CHARLES ED. HAVILAND, a citizen of the United States, residing at Limoges, in the Republic of France, have 5 invented and produced a certain new and useful Design for Dishes, fully described and represented in the following specification and the accompanying illustrations, forming a part of the same.

10 In said illustrations, Figure 1 is a perspective view of a plate and saucer embodying the design. Fig. 2 is a similar view of a deep dish and its cover, both embodying the design, the cover being removed from the dish.

15 The distinguishing features of the design are the shape or outline of the edge of the piece and the surface ornamentation near said edge. The shape or outline of the edge of the piece is made up in part of scallops 3,

20 which are arranged in groups of three. Upon each side of each group of scallops the edge curves inward for a short distance, making a

depression, as shown at 4, and then outward, making a projection 5 of considerable extent. The surface ornamentation consists of depressions 2, formed in the surface of the piece below or within, as the case may be, the middle scallop 3 of each group, and which vanish as they recede from the edge of the piece. The surface ornamentation also includes an 25 irregular border 6, formed in relief along the edge and extending inward along the sides of the depressions 2.

What I claim is—

The design for a dish, substantially as herein shown and described.

In testimony whereof I have hereunto set my hand in the presence of two subscribing witnesses.

CHARLES ED. HAVILAND.

Witnesses:

FERNAND CHASTAINGT,
EDOUARD CHASTAINGT.
